C. H. BOKEMEYER,
TIMER FOR INTERNAL COMBUSTION ENGINES,
APPLICATION FILED DEC. 10, 1919.

1,378,833.

Patented May 24, 1921.

UNITED STATES PATENT OFFICE.

CHARLES H. BOKEMEYER, OF BALTIMORE, MARYLAND, ASSIGNOR TO THE ALPHA
TIMER AND ACCESSORIES COMPANY, OF BALTIMORE, MARYLAND, A CORPORA-
TION OF MARYLAND.

TIMER FOR INTERNAL-COMBUSTION ENGINES.

1,378,833.

Specification of Letters Patent. Patented May 24, 1921.

Application filed December 10, 1919. Serial No. 343,709.

To all whom it may concern:

Be it known that I, CHARLES H. BOKE-
MEYER, a citizen of the United States, resid-
ing at Baltimore city, State of Maryland,
5 have invented certain new and useful Im-
provements in Timers for Internal-Combus-
tion Engines, of which the following is a
specification.

This invention relates to devices for tim-
10 ing the explosions in internal-combustion
engines, and more particularly to a device
of this kind used in connection with the well-
known Ford motor.

The invention has for its object to provide
15 a timer or commutator which is very efficient
and reliable in operation, and which is so
constructed that repairs and replacements
are readily made.

The invention also has for its object to
20 provide the device with a very simple means
for connecting the current wires, the connec-
tion being also so arranged that the wires
cannot become fouled from oil.

Other objects and advantages of the in-
25 vention will be pointed out in the detailed
description appearing hereinafter, and in
order that the same may be better under-
stood, reference is had to the accompanying
drawing forming a part of this specification.

30 In the drawing—

Figure 1 is a cross-section of the device;
Fig. 2 is a front elevation thereof; Fig. 3 is
a plan view of the commutator shell; Fig. 4
is a rear elevation of said shell; Fig. 5 is
35 an edge view of a contact supporting mem-
ber; Fig. 6 is a rear elevation of said mem-
ber, and Fig. 7 is a sectional detail on the
line 7—7 of Fig. 6.

Referring specifically to the drawing, 10
40 denotes the usual shell of the commutator,
the same being provided with a radial arm
11 for connection of the pull rod of the spark
lever mechanism. The shell 10 is rotatably
supported as usual on a bearing 12 on the
45 engine cover 12a. The cam shaft 13 passes
into the shell 10 and on the inside of the
latter it is fitted with a brush which operates
in connection with the commutator contact
points to make and break the primary cir-
50 cuit.

The commutator contact points are shown
at 14, they being embedded in a disk 15 of
insulating material flush with the face of the
latter. Preferably, the contact points are

made of phosphor bronze and the disk is 55
made of condensite, these two materials hav-
ing substantially the same wearing qualities.
An even wear is therefore had and the brush
will not wear the surface over which it
travels rough. If any uneven wear or rough- 60
ness should occur, the disk 15 can be re-
moved from the shell 10 and smoothed down
by a grinding or other process. The man-
ner in which the disk 15 is mounted in the
shell 10 for ready removal will be presently 65
described.

From each contact point 14 leads a wire 16,
the same being embedded in the disk 15, and
on the rear face of the latter is an enlarge-
ment or protuberance 17 to which the re- 70
spective wires lead. In the part 17 are em-
bedded metallic socket pieces 18 to which the
wires 16 are connected, and adapted to enter
these socket pieces are plugs 19 carried by a
block 20 of insulating material. The pri- 75
mary wires 21 are connected to the plugs
19 as shown in Fig. 1, and said wires are
housed in a flexible, metallic sheath 22.
The side of the shell 10 has an opening for
insertion of the block 20 to engage the plugs 80
19 with the sockets 18, and from this open-
ing extends a threaded nipple 24 on which
is screwed a closure sleeve 25.

It will be seen from the foregoing that the
wiring of the commutator is completely 85
housed in so that it cannot get oil soaked
or fouled, and it is also protected against
wear.

In order that the plugs 19 may be insert-
ed into the proper sockets 18, the interior of 90
the nipple 24 has a longitudinal rib 26 and
the side of the block 20 has a groove 27 to
seat said rib and thus center the block. The
block 20 can therefore be inserted in one
way only, and that the right way to prop- 95
erly enter the plugs 19 into the sockets 18.

The disk 15 is removably mounted in the
shell 10, and it is fastened therein by
screws 27 passing through the front wall
of the shell and threaded into the disk. On 100
the side wall of the shell 10 are lugs 28,
and the disk 15 has peripheral notches 29 to
slip over said lugs, whereby the disk is prop-
erly guided and centered when it is inserted
into the shell.

105 The brush which wipes across the contact
points 14 is a plug 30 of vanadium steel
which is fitted at its outer end with a cap 31.

of tungsten, the latter being the contacting portion of the brush. The tungsten cap has been found after thorough tests to give the best results, and as it is renewable, replacement can be readily made when necessary. The plug 30 seats slidably in a socket 32, and it is spring backed as shown at 33, so that the cap makes a firm contact at all times. The socket 32 is in the outer end of a member 34 which is hinged or pivoted, as shown at 35, to a hub or sleeve member 36 fastened to the cam shaft 13 in the conventional manner. A spring 37 also presses against the supporting member 34 of the plug 30, and tends to urge the same in the direction of the contact points 14.

The disk 15 faces the end of the cam shaft 13 and has a central aperture 38 to clear said shaft end as shown in Fig. 1.

It will be seen from the foregoing that the shell, the contact carrying disk and the brush assembly make up the complete commutator assembly, and as these parts are separate units, they are readily removable for repairs or replacement.

I claim:

1. In a commutator, a shell, a disk of insulating material removably mounted in the

shell, contact points embedded in the disk, and coöperating means on the shell and the disk for centering the latter in the former, said means comprising lugs on the wall of the shell, and notches in the periphery of the disk in which said lugs seat.

2. In a commutator, a shell having a side opening, a disk of insulating material removably mounted in the shell and having a protuberance on one side, contact points embedded in the disk and exposed on one side thereof, socket pieces carried by the aforesaid protuberance and electrically connected to the contact points, said socket pieces being positioned opposite the side opening of the shell, terminal plugs adapted to be inserted into the aforesaid socket pieces, and a supporting member for the terminal plugs insertible through the side opening of the shell to engage the plugs with the socket pieces, said opening and the supporting member having coacting means for centering the latter, and coöperating means on the shell and the disk for centering the disk in the shell.

In testimony whereof I affix my signature.

CHARLES H. BOKEMEYER.
